UNITED STATES PATENT OFFICE.

HARVEY J. YAGER, OF SEATTLE, WASHINGTON.

COLLAPSIBLE AND PORTABLE CORE FORM.

Application filed September 30, 1926. Serial No. 138,689.

This invention relates to collapsible and portable core forms for molds of that type used in building concrete chimneys, elevator shafts and other hollow structures, and more particularly to improvements in the collapsible and portable core forms forming the subject-matter of my U. S. Letters Patent No. 1,591,907, granted July 6, 1926, and my copending application filed April 29, 1926 and serially numbered 105,431.

The present invention has for one of its objects to provide a core form of the types shown in said patent and application wherein the removable corner strips shall each embody right angularly related members having their vertical edges beveled for contact with the beveled vertical edges of the sides of the core form.

A further object of the invention is to improve and simplify the means for supporting the core form in the structure being built, and to attain this end comprehends the employment of beams each consisting of but a single member and provided at its ends with hooks adapted to be removably engaged with eyes or loops carried by the structure being built.

With the foregoing and other objects in view, the nature of which will become apparent as the description proceeds, the invention consists of the novel construction, combination and arrangement of parts hereinafter fully described and claimed, and illustrated in the accompanying drawings, wherein:

Figure 1 is a sectional view taken on a plane extending vertically through the core form and a finished section of a chimney or elevator shaft, the core form being shown in position to permit the building of another section of the chimney or elevator shaft,

Figure 2 is a sectional view taken on a plane extending horizontally through the core form, chimney or elevator shaft and outside form,

Figure 3 is a detail sectional view taken on the horizontal plane indicated by the line 3—3 of Figure 1,

Figure 4 is a similar view taken on the vertical plane indicated by the line 4—4 of Figure 3, and

Figure 5 is a detail plan view of the cap.

Corresponding and like parts are referred to in the following description, and designated in the several views of the accom-

panying drawings, by similar reference characters.

The mold of which the core form forms a part includes an outside form which is of the usual construction and comprises sheeting boards 1, studs 2 and wale pieces 3.

The core form comprises opposite sides 4 and 4^a and opposite sides 5 and 5^a. The sides 4—5^a contact at diagonally opposite corners of the core form, and at the other diagonally opposite corners of the core form the vertical edges of the sides are spaced and beveled as shown at 6. Strips 7 each of which embodies right angularly related members, are removably positioned at said other diagonally opposite corners of the core form. The corner strips 7 are of a length equal to the vertical dimension of the core form, and their vertical edges are beveled and contact with the beveled edges 6 of the sides 4—5^a. Wale pieces 8 are secured to the sides 4 and 4^a, and wale pieces 9 to the sides 5 and 5^a. The wale pieces 8 terminate short of the vertical edges of the sides 4 and 4^a and the ends thereof are inclined with respect to the vertical. The wale pieces 9 extend to the vertical edges of the sides 5 and 5^a, and are provided at their ends with recesses 10 for the reception of the ends of the wale pieces 8. The recesses 10 present each wale piece 9 with shoulders 10^a and 10^b and extensions 10^c of which the latter have vertical inner sides. The shoulders 10^a are vertical and contact with the wale pieces 8, and the shoulders 10^b are inclined with respect to the vertical and spaced from these wale pieces.

At diagonally opposite corners of the core form, the shoulders 10^b of the wale pieces 9 contact with the wale pieces 8, and at these points wedges 11 are positioned between the ends of the wale pieces 8 and the extensions 10^c of the wale pieces 9. At the other diagonally opposite corners of the core form, wedges 12 are positioned between the wale pieces 8 and the shoulders 10^b of the wale pieces 9, and wedges 13 are positioned between the ends of the wale pieces 8 and the extensions 10^c of the wale pieces 9. The shoulders 10^b of the lowermost wale pieces 9 and the ends of the lowermost wale pieces 8 incline downwardly and outwardly so as to permit the wedges between these parts to be displaced in a downward direction, these wedges being secured against casual displacement by nails 14. In the lower portion of the core form there is comparatively

little room in which to work, and this arrangement of the lowermost wedges permits them to be easily and quickly displaced when it is desired to take the core form apart 5 after completing a section of the structure being molded. The arrangement of the ends of the wale pieces 8 and 9 in overlapping relation together with the wedges 11, 12 and 13 render it impossible for the pressure 10 exerted on the core form by the concrete to move the sides 4-5^a out of alignment at the corners thereof.

To hold the sides 4-5^a against outward displacement while assembling the core form 15 and pouring the concrete, there is provided a cap 15 which is in the form of an open frame and the sides of which are of angular form in cross section. The cap 15 is adapted to be applied to the upper end of the core form 20 with the horizontal members 15^a of its sides in contact with the upper edge of the core form and with the vertical members 15^b of its sides in contact with the outer surfaces of the core form. The cap 15 is preferably 25 made of metal, and the weight thereof maintains it in place against casual displacement.

The core form is adapted to be used for building an entire chimney, elevator shaft or other hollow structure. After a section 30 of the structure is completed, the outside form and core form are taken apart and removed and again erected and supported in an upwardly extending position with respect to the completed structure, as clearly illustrated in Figure 1. In this figure and in Figure 2, 16 designates the partly completed structure.

The core form is supported by scaffold planks 17 which are in turn supported by 40 beams 18. The planks 17 and beams 18 are supported within the upper end of the completed section of the structure 16, and the beams, of which each consists of but a single member, are removably connected to supporting eyes or loops 19 which are embedded in the structure during the erection thereof. The beams 18 are removably connected to the eyes or loops 19 by the hooked terminals 20 of plates or shoes 21 secured to the under 45 sides of the beams by screws 22 and eye bolts 23. The eye bolts 23 may be used for the purpose of supporting a scaffold within the structure 16, and pass entirely through the beams 18 and plates or shoes 21. Nuts 24 applied to the eye bolts 23 and contacting with the plates or shoes 21, and nuts 25 applied to said bolts and contacting with the upper sides of the beams 18, function to firmly secure the plates or shoes and eye bolts in 50 place. To permit the scaffold planks 17 and beams 18 to be removed from the completed section of the structure 16 after the removal of the core form, cables 26 are provided and are connected to said planks and beams.

55 Opposite sides of the core form are pro-

vided in their outer faces with recesses 27 for the reception of the closed ends of the eyes or loops 19 which are preferably of U-form and have the terminal portions of their side members bent downwardly to provide 70 anchoring elements 19^a. The recesses 27 are preferably formed in the sides 4 and 4^a and in the corner strips 7. As the eyes or loops 19 are carried by the core form, they are embedded in each section of the structure 16 75 during the erection of the section. The scaffold planks 17 and beams 18 may therefore be supported within a completed section of the structure 16 in a manner to support the core form in upwardly projected relation 80 with respect to the section. To prevent mortar from accumulating in the recesses 27, and thus locking the eyes or loops 19 to the core form, the recesses are closed by plates 28 after the eyes or loops are inserted therein, 85 and the plates are secured in place by nails 29. Horizontal reinforcing bars 30 are embedded in the structure 16 immediately below the eyes or loops 19 and inwardly of their anchoring elements 19^a, and to permit 90 of the ready application of these parts they are secured to the eyes or loops by tie wires 31. Vertical reinforcing bars 32 for the structure 16 are secured to the horizontal reinforcing bars 30 by tie wires 33. 95

From the foregoing description, taken in connection with the accompanying drawings, it will be understood that the core form may be readily taken apart and removed from a completed section of the structure, that the core form may be readily erected and supported from and in upwardly projecting relation to such section, and that as the section of the structure is completed the eyes or loops 19 are embedded therein so as to make provision for supporting the beams 18. The transverse members of the eyes or loops 19 are spaced a considerable distance from the inner faces of the completed structure in order to enable the hooked terminals 20 of the plates 21 to be readily engaged with the eyes or loops. The eyes or loops 19 cannot pull out of the structure under the load sustained thereby, due to their anchoring elements 19^a and the reinforcing bars 30. 110 115

It should be understood that the drawings are merely illustrative and do not pretend to give exact proportions. Furthermore, the said drawings are illustrative of a preferred construction, it being my expectation that various changes and modifications may be made without departing from the spirit and scope of my invention. 120

What is claimed is:-

1. In combination, a core form, members 125 removably connected to the core form and adapted to be embedded in the structure being built, and a core form supporting member adapted to be supported from the structure by said first named members. 130

2. In combination, a core form, eyes removably secured to the core form and adapted to be embedded in the structure being built, and a core form supporting beam provided with terminal hooks adapted to be engaged with said eyes.

3. A core form support comprising eyes

adapted to be embedded in the structure being built, said eyes having anchoring elements angularly related thereto, and a beam 10 provided with hooks removably engaged with the eyes.

In testimony whereof I affix my signature.

HARVEY J. YAGER.
